[57] **CLAIM**

The ornamental design for an electrical control housing assembly, as shown and described.

DESCRIPTION

FIG. 1 is a top plan view of an electrical control housing assembly showing my new design;

FIG. 2 is a side elevational view thereof;

FIG. 3 is a rear elevational view thereof;

FIG. 4 is a front elevational view thereof;

FIG. 5 is an elevational view of the side opposite to that

shown in FIG. 2; and

FIG. 6 is a bottom plan view thereof.
